UNITED STATES PATENT OFFICE.

EDWARD ERICKSON, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

MACHINE FOR OPERATING ON SHOE BOTTOMS.

Original application filed June 4, 1917, Serial No. 172,658. Divided and this application filed December 4, 1919. Serial No. 342,406. Renewed March 28, 1923.

To all whom it may concern:

Be it known that I, EDWARD ERICKSON, a citizen of the United States, residing at Beverly, in the county of Essex and State of Massachusetts, have invented certain new and useful Improvements in Machines for Operating on Shoe Bottoms; and I do hereby declare the following to be a full, clear, and exact description of the invention, such 10 as will enable others skilled in the art to which it appertains to make and use the same.

This invention relates to machines for operating on shoes in a partial state of completion and more particularly to tacker mechanisms for securing certain parts together.

The present application is a division of my Letters Patent of the United States No. 20 1,373,553, granted April 5, 1921, which discloses a machine that is adapted to position the welt ends for the butting operation, produce a bevel or scarf on each welt end and tack the upper to the insole at the point 25 where the welt ends are butted. The claims of said patent are directed to the general organization of a welt butting and tacking machine, while the present application is concerned with tacker mechanisms of the kind 30 disclosed whether or not embodied in a machine having a welt butting mechanism.

The object of the present invention is to improve the construction and mode of operation of tacker mechanisms, providing for 35 their operation at increased speed, with greater efficiency, and with less loss of power.

To the accomplishment of this object and such other objects as may hereinafter appear, as will be apparent to those skilled in the 40 art, the features of the invention relate to certain devices, combinations and arrangement of parts hereinafter described and particularly pointed out in the appended claims.

The preferred form of the invention is illustrated in the accompanying drawings, in which:

Figure 1 is an elevation of the left hand side of the entire machine with portions of the frame broken away to disclose certain 50 parts of the operating mechanism; Fig. 2 is a sectional plan, on the line 2—2 of Fig. 1, of the operating mechanism for the welt butting knives; Fig. 3 is a detail, in elevation, with certain parts of the frame broken

away, of the inside face of the right hand side frame; Fig. 3^a is a detail in perspective of parts shown in Fig. 3; Fig. 4 is a detail, in a vertical section, of the lower end of the tacker mechanism; Figs. 5, 6 and 7 are details illustrating different positions of the welt 55 butting knives and of the tacker mechanism at different times during the welt butting and tacking operations; Fig. 8 is a vertical section of the driving shaft and its actuating mechanism on the line 8—8 of Fig. 1; and Fig. 9 is an end elevation of the clutch and 60 clutch operating mechanism at the right hand side of the machine.

The invention is illustrated as embodied in the combined welt butting and tacking machine disclosed in said Patent No. 1,373,553, which machine is provided with mechanism for positioning both welt ends for the butting operation, mechanism for butting both welt ends simultaneously, and mechanism 70 for thereafter inserting tacks to secure the upper which has been fastened in by the welt positioning operation. In connection with the description of the tacker mechanism constituting the subject matter of the present application, therefore, it will be necessary to describe also the illustrated welt positioning and welt butting instrumentalities.

In the embodiment of the invention illustrated in the drawings and referring first to Figs. 1, 2 and 3, the mechanism for positioning and butting both welt ends, and the tacker mechanism are mounted upon a head supported upon a column 15, said head having a forwardly projecting goose neck 17 at the front of which are journaled vertical pivot rods 19 and 21 on which are supported the swinging side frames 23 and 25. The side frames, as will be described later, support the welt butting and tacking mechanisms with the exception of the tack delivering mechanism, comprising a tack pot 27, the supporting frame of which is secured to a bracket 29 bolted to a table 31 cast at the upper side of the goose neck 17 (Fig. 1).

The moving parts are driven by the rotation of a driving shaft 33 (Figs. 1 and 8) which extends transversely of the head and is journaled in bearings 35 and 37 (Fig. 8) at the rear of the machine provided beneath the guard plate 39 (Fig. 1). The driving shaft is normally at rest but may be connected at the will of the operator to a power shaft 41

which is continuously driven by a belt running over a pulley 43 (Fig. 1).

As is usual in machines of this character the shoe is supported and positioned vertically for the welt-butting and tacking operations by means of thin plates, usually termed welt supports, which are inserted in the welt crease at each side of the shoe substantially at the rear end of the inseam. Each of the 5 swinging side frames 23 and 25 carries one of these welt supports. The welt support 47 for the right-hand side frame is best illustrated in Fig. 3, while both of these supports are shown in dotted lines in Fig. 2, 10 in position beneath the welt ends. It will be understood that, as is usual in this type of machine, the welt supports are forced into the welt crease by the inward movement of the swinging side frames 23 and 25 about their 15 pivot rods 19 and 21. The consequent pressure exerted on the welt crease by the welt supports causes the upper, just in advance of the heel seat tacks, to be properly lasted in.

25 In order to position the shoe for the proper engagement of the welt supports with the welt crease, the machine is provided with a back gage 53 which may be adjusted longitudinally so as to locate the heels of 30 shoes of different sizes properly for the inward movement of the welt supports. As the back gage adjusting mechanism forms no part of the present invention, it is not here described, reference being made to said Patent 35 No. 1,373,553 for a detailed description thereof.

The forward ends of the swinging side frames 23 and 25 are normally held apart by means of a spring 87 (Fig. 2) the ends of 40 which are attached to pins projecting from the rear ends of the side frames. In order that the two frames 23 and 25 may move together, they are provided with intermeshing toothed segments 89 and 91 respectively, 45 through which the lower ends of the rods 19 and 21 extend. Treadle mechanism is provided to overcome the force of the spring 87 and bring the forward ends of the swinging side frames into position to support a 50 shoe for the operations to be performed thereon. The operating treadle 93 (Fig. 1) is pivoted at 95 in the lower part of the column 15 and is connected by a treadle rod 97 to the horizontal arm 99 of a bell-crank 55 lever pinned to a transverse rock-shaft 101 journaled in the lower part of the machine head. The vertical arm 103 of this bell-crank lever is provided with a socket which receives one end of a coil spring 105, 60 the other end of which bears in a socket formed in the arm 107 which projects upwardly and has two legs 109, one at each side of the bell crank 99-103, by means of which it is loosely pivoted on the rock-shaft 65 101. The upper end of the lever 107 is pro-

vided with a horizontal head in each end of which there is formed a socket 110 for the reception of the inner ends of struts 111 which extend between the head and sockets 113 (Fig. 2) for their outer ends, formed at the rear ends of the swinging side frames 23 and 25. The treadle is normally held raised by a spring 115 (Fig. 1) connecting it to the column 15 so that normally the spring 105 is not under tension. When the treadle is depressed, however, the lowering of the treadle rod 97 operates through the bell-crank lever 99-103, and the spring 105, to move the vertical arm 107 to the left (Fig. 1) which operates on the inner ends of the two struts 111 so as to bring the struts into a position approaching alinement, and consequently forces the rear ends of the side frames apart, stretching the spring 87, as is shown in Fig. 2. This outward movement of the rear ends of the side frames causes an inward movement of their front ends and brings the welt supports into the welt crease of the shoe which has previously been placed with its heel against the back gage 53 and which is held by the operative at a proper height to receive the welt supports in the welt crease. Means may be provided to limit the opening movement of the side frames to a degree commensurate with the width of the shoe to be operated upon, such as is clearly disclosed in said Patent No. 1,373,553.

It will be observed that on pressing the treadle 93 only so much pressure can be placed upon the welt crease by the supporting plates as is permitted by the strength of the spring 105 (Fig. 1) for, as soon as the pressure equals the strength of the spring, the spring will begin to compress without further movement of the arm 107 or further straightening of the toggle formed by the struts 111. The strength of the spring 105 may be varied by an adjustment of a threaded block 106 to suit the strength of the material which is being operated upon. Continued depression of the treadle will, however, continue to rock the shaft 101 which movement sets in motion the driving mechanism for operating the moving parts of the machine, such parts comprising the welt-butting knives, the tacker mechanisms and tack delivering mechanism contained within the tack pot.

Referring now more particularly to Figs. 1 and 8, the power shaft 41, which extends longitudinally in the machine and is supported in a journal at the rear of the machine head, carries intermediate its length a spiral gear 125 which drives a second spiral gear 127, the hub 129 of which has a bearing upon the driving shaft 33. Connected by a suitable driving joint to the hub 129 is a sleeve 131, which forms the bearing for a Horton clutch. This clutch, as is usual, is

provided with a clutch ring 133 formed as a part of the bearing sleeve 131, a cam ring 135 which is keyed to the driving shaft 33, a roll carrier 137 with its rolls 139, interposed between the clutch ring and cam ring, and an operating spring 141 (dotted lines Fig. 9). It is thus seen that the spiral-gear hub 129 and clutch-ring hub 131 form a hollow shaft which is continuously driven from the power shaft. Interposed between the driving shaft bearing 37 and the spiral gear 127 is a suitable thrust bearing 143. Between the two bearings 35 and 37 of the driving shaft 33 and located on the median line of the two swinging side arms is a crank 145 (Figs. 1 and 8), the rotation of which, through connections to be described later, operates the welt-butting knives and tacker mechanisms. At the left hand end of the shaft 33 outside the machine frame, there is secured a disk 147 which carries a wrist pin 149 to which is connected, by the yoke shown in Fig. 1, a pitman 151 which, through its reciprocations, operates the mechanism for delivering tacks to the tack tubes for delivery to the tacker nozzles.

On the right hand end of the rock-shaft 101 is an arm 153 (Figs. 1 and 9) which carries the adjustable tappet 155. When the shaft 101 is rocked sufficiently by pressure on the treadle 93, the tappet 155 engages the forwardly projecting arm 157 of the three-armed lever pivoted loosely upon a horizontal stud 159 (Figs. 8 and 9) carried by the machine frame, and the movement thus imparted to this lever causes the Horton clutch to become engaged, to rotate the driving shaft 33 through a single revolution, by means now to be described. The rearwardly projecting arm 161 of the three-armed lever has pivoted thereto, by its lower end, an upwardly projecting rod 163 which passes through a yoke formed at the forward end of a horizontally disposed lever 165 pivoted upon a second stud 167 threaded into the machine frame. The lever 165 carries at the rear side of the stud 167, an arm 169 which supports the usual yielding buffer 171 adapted to be engaged by the usual stop shoulder on the Horton clutch at the time the clutch is disconnected. The lever 165 also has secured thereto a tooth 173 which is engaged by a shoulder 175 cut in the rear edge of the vertical rod 163. A spring 177 connected at its forward end to the rod 163 and at its rear end to the buffer supporting arm 169 normally holds the buffer in position for stopping the clutch and draws the rod 163 rearward into engagement with the tooth 173. A second spring 179 connected at its forward end to the third arm 181 of the three-armed lever hereinbefore referred to, and by its rear end to a pin 183 (Fig. 8) carried by the machine frame normally maintains the tappet engaging arm 157 of

the lever in raised position and holds the shoulder 175 below the tooth 173.

The driving shaft 33 also has secured thereto a brake wheel 185, which, at the time the clutch is disconnected, is engaged by a brake shoe 187 which, as shown in Fig. 9, partially surrounds the brake wheel. The brake shoe is mounted upon an eccentric bearing 189 which, in turn, is carried upon a reduced portion 191 of the hub of the lever arm 165 (Fig. 8). The eccentric bearing is formed as a split ring and is secured to the reduced hub 191 by means of a clamping bolt 193 (Fig. 9). A cap plate 195 holds all of these parts in place on the stud 167. It is readily seen that with this construction whenever the buffer arm 169 is thrown inward to disconnect the Horton clutch the eccentric bearing 189 is rotated and moves the brake shoe 187 into engagement with the brake wheel 185, and vice versa a movement of the buffer arm to the right, in Fig. 9, to permit the clutch to operate will, by a reverse rotation of the eccentric mounting 189, withdraw the brake shoe from the brake wheel. By loosening the cap plate 195 and the bolt 193 the eccentric bearing may be adjusted angularly as may be necessary to increase its throw whenever it becomes desirable to do this by reason of wear of the parts of the brake.

The operation of these parts will be understood best from Fig. 9, it being apparent that when the tappet 155 descends the three-armed lever is rotated on its pivot in a direction to raise the rod 163 and consequently, through engagement of the shoulder 175 with the tooth 173, rock the lever 165 in a direction to withdraw the buffer 171 from its engagement with the stop of the Horton clutch. Simultaneously with this movement the brake is released and the spring 141 of the Horton clutch moves the roll carrier in a direction to cause the rolls to bind and drive the shaft 33.

It is not desired, however, that it be necessary for the operative to maintain his foot on the treadle while the driving shaft is rotating and the welt-butting and tacker mechanisms are being operated. Some means must be provided, therefore, for locking the swinging side frames in the position to which they have been moved by the depression of the treadle. Such a locking mechanism is illustrated in Fig. 1 and comprises a vertical arm not shown secured to the rock-shaft 101 having pivoted to its upper end the forward end of a rectangular rod 197 the rear end of which extends through a rectangular opening in the arm 199, depending from, and pivoted freely on, a horizontal stud 201 carried by the machine frame. The free end of the arm 199 is normally pulled forward by a spring 203 connected between the arm and the frame.

When the machine is in a position of rest a pin 205 on the disk 147 at the end of the driving shaft is in engagement with an upwardly projecting ear 207 carried by the arm 199 and maintains this arm in such position that the rod 197 can slide freely through the rectangular opening in the arm. As soon as the driving shaft 33 begins to rotate, however, the pin 205 is removed from its engagement with the ear 207 and this permits the spring 203 to rock the arm 199 to an angular position with relation to the rod 197 whereby the corners of the opening in the arm above and below the rod will bind on the rod and act as a lock to prevent the rock-shaft 101 from rotating under the influence of the extended treadle spring 115.

In order to hold the rotation of the driving shaft to a single revolution, the roll carrier 137 of the Horton clutch is provided with a radial pin 209 (dotted lines Fig. 9) which, on the clockwise rotation of the driving shaft 33, engages the upper end of the rod 163, pushing this rod forward about its pivot and withdrawing the shoulder 175 from beneath the tooth 173. The spring 177 immediately acts to pull the clutch buffer 171 into position to be engaged by the clutch stop, at the same time applying the brake, by reason of the angular movement imparted by the movement of the lever 165, to the eccentric brake bearing 189. Before the machine stops, however, the pin 205 on the disk 147 (Fig. 1) engages the ear 207 of the lock arm 199 and turns this arm to a position normal to the rod 197, so as to release the clutch operating tappet 155 to the influence of the spring 105 and also the side frames to the influence of the treadle spring 115. Consequently, the tappet 155 is withdrawn from engagement with the three-armed lever, the spring 179 is enabled to return the clutch operating parts to the position shown in Fig. 9, and the spring 87 which connects the rear ends of the side frames operates to open the frames about their pivot rods 19 and 21 and thus release the shoe from its engagement by the welt supporting plates 45 and 47. In the meantime, during the single revolution of the driving shaft, the two welt ends have been butted and two tacks, one at each side of the shoe, have been driven.

The shoe having been positioned by the depression of the treadle, the driving shaft having been connected to the power shaft by the actuation of the driving shaft clutch, and a tack having on the previous operation been delivered to each of the tack tubes 219 (see Fig. 4) in the manner fully explained in said Patent No. 1,373,553, the welt is then butted and subsequently tacked by the instrumentalities now to be described.

Referring now to Fig. 1, the crank 145

of the driving shaft 33 is connected by a pitman 272 to a piston 275 which is guided within a cylindrical way 277 cast centrally in the lower part of the goose neck 17. Projecting from the forward end of the piston 275 is a connecting rod 279 provided with an H-shaped head 281 (see dotted lines, Fig. 2) which lies horizontally, with the legs of the H pointing outwardly toward the side frames 23 and 25. The slots 283 and 285 formed between the legs of the H carry cubical slide blocks 287 and 289 which are drilled vertically for the reception therethrough of vertical pins carried by the welt-butting knife operating slides 291 and 293. With this construction, a rotation of the crank 145 to withdraw the piston 275 within its guideway causes the slides 291 and 293 to withdraw and operate the welt-butting and tacking mechanism.

As the side frames 23 and 25 which form the guides for the slides 291 and 293 are usually at an angle to the line of movement of the piston 275, the slots 283 and 285 in the head 281 provide for an outward movement of the connecting blocks 287 and 289 as the slides are withdrawn. Since the mechanism carried by each of the side frames is similar, it will be sufficient to describe the mechanism at one side only. The mechanism upon the side frame 25 at the right hand side of the machine will be used for this purpose.

Referring more particularly to Fig. 3, which illustrates the various mechanisms on the side frame 25 in a position of rest, the welt-butting-knife slide 293 is connected to the block 289 by a pin 295 which extends between two inwardly projecting ears at the rear end of the slide. The slide rests upon a flat track, or way, 297 formed on the lower portion of the side frame 25. The slide is T-shaped in cross-section and is guided during its rearward movement by the side walls of the swinging frame which are recessed to overlap its T-head (see broken away parts of Fig. 1). The upper part of the slide 293 is channel shaped for the greater portion of its length and its side walls are cut and drilled at two separate points for the reception of the lower cylindrical ends of two links 299. The upper ends of these links are received in similar openings formed in a channel shaped welt-butting knife carrier 301 (Fig. 3) but the link openings in the carrier are further apart than those in the slide, as shown in Figs. 5 to 7. This mounting of the knife carrier permits it to be rocked back and forth relatively to the knife slide to lower and raise the welt-butting knife relatively to the shoe. The movement in a rearward direction is limited by the end of the carrier abutting against a shoulder 303 (Fig. 7) formed on the slide and a movement in a forward direc-

tion is limited by the engagement of an adjustable stop screw 305 (see Fig. 5) with the surface of the nose 307 of the slide. The welt-butting knife 309 which extends inward laterally from the carrier (see Fig. 2) is clamped to the end of the carrier in a dove-tail slot by means of a block 311 (Fig. 3) having a pin extending forwardly through a downwardly projecting portion 10 of the end of the carrier and secured in place by a nut. Just in front of the knife is a welt presser 313 (Fig. 2).

The movement of the welt-butting knife slides 291 and 293 actuates also the tacker mechanism. Referring to Fig. 3 for a disclosure of the tacker mechanism, the forward edge of each swinging side frame is grooved vertically to form a rectangular way 343 which is closed by a face plate 345 (see also Fig. 1). Within this way is seated, for vertical sliding movement, the driver slide 347. This slide 347 is bored longitudinally for the greater part of its length for reception of the cylindrical driver bar 349. At its lower end the slide 347 is provided with a reduced bore through which the tack driver 351 extends (Fig. 4). The tack driver is secured to the lower end of the driver bar by a nipple 353 in the usual manner. Also the lower end of the driver slide has secured thereto, by a second nipple 355, a suitable tack nozzle 357. At its upper end the driver bar is provided with a shoulder in the form of a head 359 (Fig. 3) the rear end of which is bifurcated and embraces the two sides of a vertical track 361 formed on the side frame. A roll is carried by the head 359 which engages the track 361 and guides the bar in its movement through the driver slide. The extreme upper end of the driver bar carries a conical cap 363 which is engaged by a socket on one end of the coiled driving spring 365. The other end of the driving spring is connected to a block 367 having a pin secured in a bearing 369 (see Fig. 1) at the rear side of the driver slide. Pivoted by its lower end, at 371, in a vertical slot formed for its reception at the upper end of the face plate 345 is a latch lever 373 (dotted lines Fig. 3) carrying at its upper end a roll 375 which is normally held in the path of movement of the driver bar head 359 by means of a spring pressed pin 377. The inward movement of the lever 373 is limited by a lug on the lever engaging a stop pin 381 mounted in the face plate. The driver head 359 is provided with a beveled surface 383 so located that on the upward movement of the driver bar the roll 375 is cammed to one side until the head has reached a position above the roll when the roll snaps back beneath the head and supports the driver bar against downward movement. The latch lever 373 is also provided with a cam piece 385 which pro-

jects into the path of and is adapted to be engaged by a cam piece 387, formed at the upper end of the driver bar slide, when said slide descends. The purpose of this action will presently be described. The driver bar 70 slide is provided at its rear side with teeth 389 and forms, in effect, a rack which is engaged by the teeth of a segment 391 carried by a shaft 393 journaled in the side frame. The segment is provided with a 75 downwardly projecting part which forms a crank arm and is connected at its lower extremity by a link 395 to an arm 397 extending upwardly from and integral with the welt-butting knife carrier 301 (see Fig. 3). 80 All the moving parts just described are held within the swinging side frame 25 by a cover plate (not shown) suitably bolted on, and a similar cover plate 24 is provided for the side frame 23 (see Fig. 1). 85

Referring now particularly to Figs. 5, 6 and 7, and remembering that the moving parts, just prior to the welt butting operation, are in the relative positions shown in Fig. 3, when the driving shaft 33 commences 90 to rotate the piston 275 and its H-shaped head 281 are drawn backwardly, or away from the operative which causes the welt-butting knife slides 291 and 293 to be drawn rearwardly. Describing now the operation of one 95 of the knives only, as the slide 293 is withdrawn on its track 297, the resistance offered by the tacker mechanism causes the links 299 to pivot about their lower ends and tilt the welt-butting knife carrier 301 forward until 100 its stop screw 305 engages the nose 307, as shown in Fig. 5. This brings the welt presser into engagement with the welt and places the knife in the plane of the surface of the guard 339, this position being determined by a proper adjustment of the screw 305. Further rearward movement of the piston 275 now draws both the slide and the carrier rearwardly together causing the knife to cut through and bevel the welt end. 105 As the welt-butting knife carrier 301 moves rearwardly it draws with it the link 395 and, by turning the segment 391, draws the driver-bar slide 347 downwardly relatively 110 to the driver-bar. The tack which has been resting in a tack-way 348 formed for its reception in the inner side of the driver-bar slide just above the nozzle 357, as shown in Fig. 4, drops into the nozzle when the driver-bar slide has been drawn down sufficiently for the trackway to come below the lower end of the driver. The tack is now in position to be driven whenever the driver is permitted to descend. The downward movement of the driver-bar slide acts to continually place tension upon the driver spring 365, since the driver-bar itself is held from downward movement by reason of its head 359 being above the roll 375 on the latch lever 373. Just as the nozzle 115 120 125 130

reaches the shoe, as shown in Fig. 6, the cam 387 on the driver-bar slide engages the cam 385 on the latch lever and pushes the latch lever to the right in Fig. 3, so as to withdraw the roll 375 from beneath the head 359 of the driver bar. This immediately releases the driver-bar to the action of the now fully tensioned driving spring 365 and the tack is driven into the shoe, the parts at this time 10 being as shown in Fig. 6. The crank 145 has now passed through a half revolution and the welt-butting knife slide 293 is again moved forward, first relatively to the carrier 301 which causes the links 299 to tilt 15 backward until the rear end of the carrier engages the shoulder 303 (see Fig. 7) thus raising the welt-butting knife from the shoe. The forward motion of the carrier 301 actuates the link 395 to reversely rotate the segment 391 and again raise the driver-bar slide 347. Since the head of the driver-bar rests at this time upon the upper end of the driver-bar slide, the driver and its driving spring are both raised together until the latch lever 373 is tilted outwardly by engagement of the cam surface 383 with the roll 275 and the head 359 eventually rests upon the roll 375.

A friction plug 399 is seated in the face 30 plate 345 and spring pressed, as shown in Fig. 3, against the forward side of the driver-bar slide 347. This plug offers sufficient resistance to prevent movement of the segment 391 during the first part of the movement of the crank 145 to lower the cutter 309, and provides means for insuring that the cutter carrier 301 is moved toward and from the welt rest about its pivotal connection with the cutter slide 293. The plug 40 performs a like function to restrain the carrier from moving relatively to the slide at the start of the return movement, thus raising the knife from the welt before the carrier is advanced by the slide to its forward 45 position ready for another cutting stroke.

Each driver-bar slide is also provided with a longitudinal groove 350 in its inner face, best shown in Fig. 4, which forms an upward extension of the tackway 348, the 50 function of which is to receive any extra tacks which may have accidentally been discharged, which may lie partially in the tack tube and tack way, and thus prevent jamming when the tacker slide is moved downwardly.

The pivot 371 of the latch lever 373 is integral with the lever and turns in a bore made for its reception at the side of the face plate 345. A recess 346 (Fig. 3a) within 55 the face plate is of such dimensions that when the lever is turned in a horizontal position the pivot may be slipped sideways out of the bore and the lever removed from the face plate.

46 The simplicity and ease of the operation

of the machine will be at once apparent to those skilled in the art. No rotary cams are used as power for driving the moving parts of both the welt-butting and tacking mechanisms is derived from a single crank motion. 70 The tacker operating mechanism is such that when the machine is at rest, with the drivers held withdrawn from the shoe, the driving spring is not under tension, thus making it easy to dismantle this mechanism whenever desired. The side frames are so constructed as to provide for carrying the drivers at an inclination to the shoe bottom as is usual, whereby the tacks are uniformly clinched on the iron heel plate of the last. Throughout, the mechanism is simple, easily assembled and sturdy.

Nothing herein contained is to be construed as limiting this invention in the scope of its application to use in connection with the particular machine or the particular mode of operation, or both, selected for purposes of illustration and explanation.

While the particulars of construction herein set forth are well suited to one form of the invention, it is not to be understood that these particulars are essential, since they may be variously modified within the skill of the artisan without departing from the true scope of the actual invention as defined in the following claims.

The nature and scope of the present invention having been indicated, and the preferred embodiment of the invention having been specifically described, what is claimed as new is:

1. A machine for operating on shoe bottoms having, in combination, tacker mechanism including a driver-bar having a driver, a driver slide movable relatively to the driver-bar, and a driving spring connected to the bar and the slide; and means for moving the slide relatively to the bar to tension the spring.

2. A machine for operating on shoe bottoms having, in combination, a tack driver slide, a driver-bar movable relatively to the slide and having a driver; a driver spring connecting the bar and slide; means for moving said parts away from the shoe together; and means for moving the driver slide and driver bar toward the shoe successively.

3. A machine for operating on shoe bottoms having, in combination, a driving spring; a tack driver-bar having a head to engage a socket on one end of said spring; means to hold said bar withdrawn from the shoe; a slide to which the other end of the spring is attached, said slide carrying a tack nozzle at its lower end, the arrangement being such that when the nozzle and slide are withdrawn from the shoe the spring is relaxed; and means to advance the slide toward the shoe to tension the spring.

4. A machine for operating on shoe bottoms having, in combination, tacker mechanism including a driver-bar having a driver, a driver slide having a tack nozzle movable relatively to the driver-bar, and a driving spring connected to the bar and the slide; a latch to hold the bar withdrawn from the shoe; means to move the slide relatively to the bar to tension the spring; and means to trip the latch after a time whereby the tensioned spring advances the bar to drive the tack in the nozzle.
5. A machine for operating on shoe bottoms having, in combination, tacker mechanism including a driver-bar having a driver, a driver slide movable relatively to the driver-bar, and a driving spring connected to the bar and the slide; a latch to hold the bar withdrawn from the shoe; means to move the slide relatively to the bar to tension the spring; and means carried by the slide to trip the latch and permit the tensioned spring to advance the driver.
6. A machine for operating on shoe bottoms having, in combination, a tacker frame; a driver slide movable on said frame toward and from the shoe; a driver-bar slideable relatively to the slide and having a shoulder; a yielding latch member supported on the frame adapted to engage said shoulder and hold the bar withdrawn from the shoe; a driving spring bearing on said bar; means to move the slide relatively to the bar; and means controlled by the movement of the slide to cause the latch member to yield and release the bar to the action of the spring.
7. A machine for operating on shoe bottoms having, in combination, a tacker frame; a driver slide movable toward and from the shoe on said frame; a driver-bar slideable relatively to the slide and having a shoulder; a laterally yielding latch member supported on the frame adapted to engage said shoulder and hold the bar withdrawn from the shoe; a driving spring connected at one end to the bar and at its other end to the slide; means to move the slide relatively to the bar to tension the spring; a cam on the latch member; and a cam on the slide adapted to engage the latch cam after the spring has been tensioned to disengage the latch from the bar.
8. A machine for operating on shoe bottoms having, in combination, a tack driver and a tack nozzle relatively movable; and a driving spring for said driver arranged so as to be tensioned by a movement of the nozzle away from the driver.
9. A machine for operating on shoe bottoms having, in combination, a tacker frame; a track driver; and a latch member seated in a slot in the frame in position to support said driver, said latch comprising a lever pivotally mounted on an integral
- stud journaled in the frame, and said slot being wider than the lever opposite the journal whereby the lever may be removed by turning it about its pivot and then moving it sidewise in the wide portion of the slot to withdraw the stud from its journal.
10. A machine for operating on shoe bottoms having, in combination, a frame; a driver-bar having a driver; a slide within which the bar operates, said slide being movable in the frame relatively to the bar; a tackway in the slide adjacent the driver; means to deliver tacks to said tackway; and means to prevent the slide from jamming if tacks are improperly delivered to the tackway.
11. A machine for operating on shoe bottoms having, in combination, a driver; a slide having a tackway so located as to hold a tack adjacent the driver and a slot extending upwardly from the receiving end of the tackway; a frame supporting the slide and driver having a tack delivery opening for delivering a tack to the tackway; and means for moving the slide downwardly relatively to the driver and said delivery opening to an extent sufficient to allow the tack to drop into the tackway below the driver, said slot being of sufficient length to maintain the delivery opening continually covered by the slot.
12. A machine for operating on shoe bottoms having, in combination, a movable tack driver-bar; a tack driver slide movable relatively to the driver-bar; and a driving spring having two ends, one of which is rigidly secured to the driver slide and the other of which engages the end of the driver-bar, the construction of the spring and the location of the points of connection being such that when the driver slide and bar are moved together the spring is relaxed, but when the slide is moved relatively to the bar the spring is tensioned.
13. A machine for operating on shoe bottoms having, in combination, a tack driver having a shoulder; a pivotally mounted plate on which said shoulder rests when the driver is withdrawn from the work; and a tacker frame having a way for said driver and a slot for receiving said plate, said slot having a portion wider than the plate where the plate is pivoted in the frame but otherwise being approximately the width of the plate.
14. A machine for operating on shoe bottoms having, in combination, a frame; a driver-bar having a driver; a slide within which the bar operates, said slide being movable in the frame relatively to the bar; a tackway in the slide adjacent the driver and a longitudinal slot in the slide above and forming a continuation of said tackway; a tack tube for delivering tacks terminating adjacent the juncture of said tack-

way and slot; and means to reciprocate said slide relatively to the driver bar.

15. A machine for operating on shoe bottoms having, in combination, a tack driver 5 slide and a tack driver bar telescopically arranged; a driving spring so connected to said elements and so proportioned that when the telescoping elements are extended the spring is placed under tension; and means 10 for moving one of said elements relatively to the other to effect such tensioning of the spring.

16. A machine for operating on shoe bottoms having, in combination, a tack driver 15 slide and a tack driver bar telescopically arranged; a driving spring having an end connected to each of said elements, said points of connection being close together when one element is housed within the other 20 and the spring being untensioned; and means for moving one of said elements relatively to the other to separate said points of connection and place the spring under tension.

17. A machine for operating on shoe bottoms having, in combination, a tack driver 25 bar having a head, a tack driver slide surrounding said bar and having a head, said heads being in engagement when the bar is housed within the slide, means for moving 30 the slide relatively to the bar, a latch member for engaging the driver bar head to hold the bar from movement while the slide is moving, means on the slide head for tripping said latch member after a predetermined movement of the slide, and a spring 35 acting on the driver bar to advance it within the slide when the latch member is tripped.

18. A machine for operating on shoe bottoms having, in combination, tacker mechanism 40 including a driver bar having a driver and a driver slide having a tack nozzle, said bar being arranged with its driver in the nozzle; means to deliver a tack to a position against the driver above the nozzle; means 45 to move the nozzle off the driver to permit said tack to enter the nozzle and to advance the nozzle toward the shoe bottom; a spring for operating the driver bar; and means 50 to cause said spring to actuate the driver bar and drive said tack from the nozzle when the advance of the nozzle has brought the tack into driving position with relation to the shoe bottom.

19. A machine for operating on shoe bottoms having, in combination, tacker mechanism 55 including a driver bar having a driver and a driver slide having a tack nozzle, said bar being arranged with its driver in the nozzle; means to deliver a tack to a position 60 against the driver above the nozzle; means to move the nozzle off the driver to permit said tack to enter the nozzle and for holding said driver bar from movement while the nozzle approaches tack driving position; a spring for operating the driver 65

bar; and means controlled by movement of the nozzle to release the driver bar to the influence of said spring.

20. A machine for operating on shoe bottoms having, in combination, a tack driver, 70 a tack nozzle within which the driver operates; means to advance the nozzle away from the driver to tack driving position; a spring to actuate the driver to drive a tack in the nozzle, said spring being restrained from operation while the nozzle is advancing; and means movable with the nozzle for releasing said spring to cause the tack to be driven.

21. A machine organized to insert tacks 80 into a shoe bottom having, in combination, means for holding a shoe in a fixed position, a tack nozzle movable toward and from the shoe, a driver arranged to drive tacks from the nozzle into the shoe, a spring for operating the driver, mechanism to move the nozzle toward and from the shoe and acting in one of said movements to place the driver spring under tension, and means controlled 85 by movement of the nozzle toward the shoe for releasing the driver.

22. A machine organized to insert tacks 90 into a shoe bottom having, in combination, means for holding a shoe in a fixed position, a tack nozzle movable toward and from the shoe, a driver arranged to drive tacks from the nozzle into the shoe, a spring for operating the driver, mechanism to move the nozzle toward and from the shoe and acting in one of said movements to place the driver 95 spring under tension, and means acting during movement of the nozzle toward the shoe 100 for releasing the driver.

23. A machine organized to insert tacks 105 into a shoe bottom having, in combination, means for holding a shoe in a fixed position, a tack nozzle movable toward and from the shoe, a driver arranged to drive tacks from the nozzle into the shoe, a spring for operating the driver, mechanism to move the nozzle toward and from the shoe and acting in one of said movements to place the driver 110 spring under tension, and means, controlled by operation of said mechanism in moving the nozzle toward the shoe, for releasing 115 the driver.

24. A machine for operating on shoe bottoms having, in combination, a tack nozzle, a driver arranged to drive a tack from said nozzle into the shoe bottom, a spring to operate the driver, a latch for restraining the driver from action when the spring is under tension, mechanism for moving the nozzle toward and from the shoe bottom and causing the spring to be placed under tension during one of its movements, and means operated by movement of said mechanism to release the latch when the nozzle has been moved into proper relation to the shoe bottom for the tack to be driven.

25. A machine for operating on shoe bottoms having, in combination, a tack nozzle, a driver arranged to drive a tack from the nozzle, a spring to operate the driver, mechanism to move the nozzle toward and from the shoe, and connections for placing the driver spring under tension by one of said movements of the nozzle and for restraining the spring from acting during movement of 5 the nozzle toward the work until the nozzle is in position for the tack to be driven, said mechanism then acting through said connections to release the spring to cause the tack to be driven.
- 10 26. A machine for operating on shoe bot-
- 25 toms having, in combination, a driver bar carrying a driver, a slide carrying a tack nozzle, power means to move said slide and tack nozzle from an upper position to receive tacks to a lower position for tack insertion, means for delivering a tack to the nozzle while the nozzle is in its upper position remote from the work, a spring for actuating the driver, connections for causing the spring to be placed under tension by 30 movement of the slide, and means controlled by the means for moving the slide to release the driver to the action of the spring.

EDWARD ERICKSON.
